WALTER H. WHITE, OF KENOSHA, WISCONSIN, ASSIGNOR TO THE BADGER BRASS MFG. CO., OF KENOSHA, WISCONSIN, A CORPORATION OF WISCONSIN.

LOCKING-RING FOR GLAZINGS.

1,144,083.

Specification of Letters Patent. Patented June 22, 1915.

Application filed December 9, 1914. Serial No. 876,211.

To all whom it may concern:

Be it known that I, WALTER HEZELTINE WHITE, a citizen of the United States, residing at Kenosha, in the county of Kenosha 5 and State of Wisconsin, have invented certain new and useful Improvements in Locking-Rings for Glazings, of which the following is a specification.

This invention relates to improvements in 10 locking rings for glazings, and is particularly well fitted for embodiment in lamps such as are used on automobiles or other vehicles.

In head-lamps such as are used upon automobiles or similar vehicles, the glazing of the lamp is usually circular in shape, and in its usual situation at the front of the lamp it constitutes a panel closure for the interior of the lamp, which is subject to a great deal 15 of mechanical abuse and is also much exposed to dirt and the action of the elements. It is, thus necessary to provide an extremely substantial and rugged construction which will prevent access of dust and moisture to 20 the interior of the lamp, while at the same time the construction used must permit of the ready replacement of a broken glazing with a new one whenever the occasion arises. Since, however, in nearly all cases the glazings 25 have become broken by slight accidents when the vehicle is out of touch with the factory in which the lamp was originally made, it is usually necessary to procure new glazings from some local repair establishment which either carries a supply of various diameters or else is equipped to cut out 30 glass disks from the sheet. These substitute glazings having been cut out of glass different from the glass which was used to 35 construct the original glazing, frequently vary widely in thickness, and the result is that sometimes they are too thick to enter the frame of the lamp, or, on the other hand, they may be so loose as to permit the glazing to rattle and allow dust and rain to enter 40 the lamp. This latter defect was formerly not of such great consequence, but at the present time, when electric head lamps are almost universally employed on automobiles, 45 the reflectors of these lamps are constructed of highly polished silver plated brass or similar material which rapidly becomes tarnished and loses its reflecting power if damp air or dust gains access to the reflector.

Among the salient objects of my present invention are, to provide a construction which is practically air and moisture proof at all times when used with glazings of various thicknesses; to provide a construction in which a broken glazing may be readily replaced with a new one without the use of special tools; to provide a construction in which the glazing is powerfully locked into its position in the front of the lamp body in such a manner as entirely to obviate any 50 of rattling when the lamp is subjected to severe vibration; to provide a construction in which are employed no perishable materials liable to deterioration through the action of the elements; to provide a construction in which the materials used are incapable of giving off gases liable to tarnish the polished surface of the reflector; to provide a construction of the class referred to in which the locking ring forms an ornamental 55 trim around the glazing opening; to provide a construction which can be manufactured extremely cheaply and accurately, and, in general, to provide a construction of the character referred to.

For the purpose of illustrating my invention, I have shown in the attached drawings, as an example of its application, an automobile head-lamp which embodies the principles referred to.

In these drawings—Figure 1 is an axial section of the lamp; Fig. 2 is a greatly enlarged fragmentary detail view of the lower portion of Fig. 1; and Fig. 3 is an enlarged section taken on the line 3—3 of Fig. 1.

In the particular lamp illustrated in the drawings, 6 represents the outer bowl or shell of the lamp, within which is inter-nested the reflector 7.

As seen more clearly in Fig. 2, the inner shell 7 and the outer shell 6 are formed with integral bead-like flanges 8 and 9, which meet together at the outer end of the lamp, the bead 9 being formed with a projecting lip or flange 10 which inter-nests 100 with the edge of the circular portion 11 of the reflector.

The portion 11 of the inner reflector and the curved part 12 of the outer shell together constitute an annular trim, circular 105 in section, around the glazing opening of the lamp and impart a considerable amount of rigidity to the combined structure, while

at the same time making the lamp neat and ornamental in its general appearance.

The bead-like flanges 8 and 9 are held together by a confining ring 13 U-shaped in section to embrace both flanges.

The lamp is equipped with the usual electrically operated bulb 14, which is seated in a socket 15 secured to the inner end of the parabolic reflector 7. Describing the 10 glazing and locking means therefor, which constitute the important feature of my invention, it will be seen that the inner curvature of the end of the reflector shell 7 is pressed out or spun to form a radially projecting flange or seat 16, which preferably forms a right-angle with an integral confining flange 17. The outer part of this shell 7 immediately adjacent the confining flanges 17, is flared outwardly, as shown at 15 18, in order to facilitate the formation of the recessed locking-ring-seat 19. This locking-ring-seat 19 just referred to is shaped in the arc of a circle, the center of which is preferably within the space between the shell 7 and the locking ring. Between the glazing 20 and the seat 16 I preferably insert an 20 annular paper gasket 21 which mitigates the harshness of the contact between the glazing and its metallic seat, while at the same time it is not apt to deteriorate or give 25 off any noxious gases which might be liable to tarnish the polished surface of the reflector. The glazing itself is tightly forced into engagement with its seat by means of 30 the annular locking ring 22, which is the essence of my invention and will now be described. This locking ring 22, as shown in Fig. 2, is constructed from an annular piece of resilient sheet metal which is 35 pressed or spun into a cross-sectional shape, the outer portion 23 of which is adapted to fit and coöperate with the arc-like seat 19, and the inner portion 24 of which is considerably flatter in curvature and obliquely 40 engages the outer face of the glazing 20. The original unflexed shape of the ring 22 is such that the end 24 presses tightly against the glazing 20, although the drawings show the latter to be of a minimum practical 45 thickness. When a comparatively thick glazing is used, the outer face of which would occupy such a position as shown by the dotted line 25 in Fig. 2, the locking ring 22 will then tend to flex or roll in its seat 50 19, as indicated by the dotted lines 26 and 27, and the extra thickness of glass will thus be accommodated without difficulty. In order to lock the ring 22 in its position and to permit of its removal when a glazing or 55 bulb is to be replaced, I sever it radially, as shown at 28 in Fig. 3, covering and locking the joint with a clamp member 29 conformed to the shape of the outside of the ring and secured in place by means of a 60 locking screw 30 which enters a nut 31 se- 65

cured to the inside of the oblique flange 18. The adjacent ends of the locking ring, when the latter is in position, are separated a sufficient distance to permit the ring to be reduced in diameter sufficiently so that it 70 may be sprung out of its seat. The outwardly exposed surface of the ring 22 is preferably nickel-plated and thus forms a handsome ornamental finishing trim around the glazing opening, which harmonizes particularly well with the outer glazing.

When making the application of my invention, it should be noted that the inner portion 24 of the locking ring is of necessity closer to the axis of the lamp than is 80 the line 32 where the seat 19 meets the outer swell 11, and, preferably, the inner edge of the locking ring where it bears against the glazing, is of considerably less diameter than said line 32 so that the cross-section of the ring, to a certain extent, is enabled to operate as a more or less resilient lever fulcrumed in the vicinity of said line 32.

Although I have shown and described 90 herein what I consider to be a preferred embodiment of my invention as applied to the particular lamp illustrated, it should be understood that the invention is not limited to the details of construction or configuration of parts described, except as specified in the appended claims.

I claim—

1. In a glazing mounting, the combination of a circumferential inclosing structure 100 provided with an inner glazing seat and an outer circumferential seat, a glazing located between said seats, and a locking ring interposed between said outer seat and said glazing and adapted to force the glazing into 105 engagement with said seat, said locking ring being formed of resilient material and having its inner edge, which engages the glazing, of a substantially less diameter than the portion of said ring in engagement with said 110 outer seat.

2. In a lamp, the combination of an inclosing structure having a pair of circular, axially spaced-apart opposed circumferential seats, a glazing mounted on one of said seats, and a resilient sheet metal locking ring interposed between said glazing and the other seat, said ring being relatively wide in its cross-section compared with the thickness of metal, and engaging one of 115 said opposed parts on a diameter substantially less than the diameter of its engagement with the other of said parts whereby said ring is capable of being compressed axially between said glazing and said second seat.

3. In a lamp, the combination of an annular supporting structure provided with an inner and an outer annular seat, a glazing supported on said inner seat, and a 120

sheet metal annular axially compressible locking ring interposed between said outer seat and said glazing.

4. In a lamp, the combination of an annular inclosing structure provided with an inner outwardly facing glazing seat and an outer recessed inwardly facing locking ring seat, said seats being spaced apart along the axis of the lamp, a glazing supported upon 10 said inner seat, a non-continuous sheet metal locking ring interposed between the outer seat and the glazing, said locking ring being axially flexible and adapted to form an annular finishing trim around the outer exposed surface of the glazing, and means for locking the ends of said ring in position.
5. In a parabolic head-lamp, the combination of a glazing provided with an annular glazing seat and a recessed outwardly projecting locking ring seat spaced along the axis of the lamp in front and outside of the glazing seat, a circular glazing supported on 20 said glazing seat and interposed between both of said seats, a non-continuous locking ring pressed out of comparatively thin resilient sheet metal and having an outer curved edge of comparatively large diameter adapted to engage the outer recessed seat and provided with an inwardly projecting edge or lip adapted to form an ornamental trim around the glazing, and means for locking the ends of said ring in position.
- 25

ed to engage the outer recessed seat, and provided with an inwardly projecting edge or lip adapted to engage the glazing on a 30 circle less in diameter than the smallest diameter of said outer seat, and means for locking the ends of said ring in position.

6. In a parabolic head-lamp, the combination of a glazing provided with an annular glazing seat and a recessed outwardly projecting locking ring seat spaced along the axis of the lamp in front and outside of the glazing seat, a circular glazing supported on 35 said glazing seat and interposed between both of said seats, a non-continuous locking ring pressed out of comparatively thin resilient sheet metal and having an outer curved edge of comparatively large 40 diameter adapted to engage the outer recessed seat and provided with an inwardly projecting edge or lip adapted to form an ornamental trim around the glazing, and means for locking the ends of said ring in position.
